UNITED STATES PATENT OFFICE.

HENRY LAWRENCE GULLINE AND IRVINE ELIAS HUTCHINS, OF GRANBY, AND ARCHIBALD IVES GILLIES, OF SHERBROOKE, CANADA; SAID HUTCHINS AND GILLIES ASSIGNORS TO SAID GULLINE.

SHEARING DEVICE.

SPECIFICATION forming part of Letters Patent No. 671,480, dated April 9, 1901.

Original application filed April 4, 1900, Serial No. 11,557. Divided and this application filed January 31, 1901. Serial No. 45,490. (No model.)

To all whom it may concern:

Be it known that we, HENRY LAWRENCE GULLINE and IRVINE ELIAS HUTCHINS, of the town of Granby, and ARCHIBALD IVES GILLIES, of Sherbrooke, in the Province of Quebec, Canada, have invented certain new and useful Improvements in Shearing Devices; and we do hereby declare that the following is a full, clear, and exact description of the same.

10 Our invention relates particularly to shearing devices for trimming the ends of horse-collar rims, and is particularly adapted for use in metal-forming machines of the type disclosed in our pending application (Case A) 15 filed on April 4, 1900, under Serial No. 11,557, of which this is a divisional part.

Our present invention may be said briefly to consist in providing a revoluble shearing-blade having cutting edges on two of its opposite sides, said blade being adapted to be automatically rotated after one cutting edge has been used to cause the other cutting edge to be brought into position to perform the next trimming required.

20 25 For a full comprehension, however, of our present invention reference must be had to the accompanying drawings, forming a part of this specification, in which like reference characters indicate the same parts, and where-

30 in— Figure 1 is a right-hand side elevation of our improved shearing device. Fig. 2 is a front elevation thereof, and Fig. 3 is a left-hand side elevation thereof.

35 The trimmer-block *b*, upon which the article to be trimmed is placed, is secured rigidly to any suitable table or stand *c* and has its forward end split and preferably provided with hardened shearing-faces *d*. A bracket *e* is 40 secured, preferably by a screw-bolt *f* and nut *g*, upon the top of the block *b* and has its forward end forked, as at *h*, and located immediately over the shearing-faces *d*.

45 The shear proper consists of a cutting disk or blade *i*, ground to present oppositely-facing cutting edges *j* and rotatably mounted upon a spindle *k*, carried in a pair of wings *l*, formed in one with a lever *m*, fulcrumed upon a pin *n*, set in the prongs of the fork *h*. A small

disk, with two diametrically opposite ratchet-teeth *o*, is mounted rigidly upon one end of the spindle *k* and is engaged by a spring-pawl *p*, carried by said lever, and a small ratchet-wheel *q* is mounted rigidly upon the other end of said spindle *k*, and a ratchet-toothed rack *r*, pivotally connected to the top of the bracket *e*, is yieldingly held in engagement with said last-mentioned ratchet-wheel by a bow-spring *s*.

The shearing-blade is perforated, as at *t*, at diametrically opposite points and is firmly locked with either cutting edge in its cutting position by a latch consisting of a resilient strip *u*, secured rigidly at one end to the lever, as at *v*, and formed adjacent to its other end with a dowel-pin *w* to take through a perforation in the side of the lever and into either of said perforations *t* in the blade as said blade is rotated by the ratchet-toothed rack *r*. This latch is lifted out of engagement with the blade by a wedge-shaped projection *z*, cast in one with a plate *3*, secured, preferably by screws, to the top of the trimmer-bracket *e*, while setscrew *4*, carried by the lever, acts as a rest for said lever when lowered to its extreme position and limits the extent of said downward movement to prevent the cutting edges of the blade being damaged.

Shearing mechanism constructed according to the foregoing will each time the lever is lowered cause one of the cutting edges of the blade to shear past its coincident shearing-face *d*, and as the operations are repeated the oppositely-facing cutting edge will shear past its coincident shearing-face, &c., the oppositely-facing cutting edges acting alternately.

It is obvious that a multisided blade can be used with a cutting edge and, if desired, a correspondingly-facing cutting edge formed at each side and the edges be caused to shear upon the same shearing-face without departing from the spirit of our invention by simply increasing the number of ratchet-teeth to correspond to the number of cutting edges.

What we claim is as follows:

1. A shearing device comprising a lever fulcrumed to a part stationary relatively to said lever; a stationary shearing edge; a blade

5 pivoted upon said lever and having two cutting edges; and means for automatically rotating said blade to have its cutting edges alternately coincide with said stationary shearing edges, substantially as described.

2. A trimming device consisting of a longitudinally-slotted lever fulcrumed at one end to a part stationary relatively to said lever and slotted in line with said lever to provide 10 shearing edges; a blade having oppositely-facing cutting edges and pivoted in the slot in said lever; and means for automatically rotating said blade to have its edges alternately coincide with the respective stationary shearing edges, as the lever is moved.

3. A trimming device consisting of a longitudinally-slotted lever fulcrumed at one end to a part stationary relatively to said lever, and slotted in line with said lever to provide 20 shearing edges; a blade having oppositely-facing cutting edges and pivoted in the slot in said lever; a ratchet-wheel on one end of said spindle; a rack pivotally connected to said stationary part and yieldingly engaging

25 said ratchet-wheel; a ratchet-wheel mounted upon the opposite end of said spindle; a spring-pawl carried by said lever and engaging the teeth of said last-mentioned ratchet-wheel; a latch carried by the lever and engaging perforations in said blade; and a wedge-shaped projection upon said stationary part to disengage said latch from the blade when the lever is moved in one direction, substantially as described and for the purpose set forth.

30 35 In testimony whereof we have affixed our signatures in presence of witnesses.

HENRY LAWRENCE GULLINE.

IRVINE ELIAS HUTCHINS.

ARCHIBALD IVES GILLIES.

Witnesses to signatures of Henry Lawrence Gulline and Irvine Elias Hutchins:
